[57] **CLAIM**

The ornamental design for a collapsible lounge chair, as shown and described.

DESCRIPTION

FIG. 1 is a right side elevational view of a collapsible lounge chair showing my new design;

FIG. 2 is a front elevational view;

FIG. 3 is a top plan view;

FIG. 4 is a rear elevational view;

FIG. 5 is a right side elevational view showing the chair in an alternate position;

FIG. 6 is a right side perspective view showing the chair in an alternate position with the cushions removed for ease of illustration;

FIG. 7 is a right side perspective view showing the chair in another alternate position with the cushions removed for ease of illustration;

FIG. 8 is a right-front perspective view showing the backrest in folded condition, the armrest in exploded condition and the cushions removed for ease of illustration; and

FIG. 9 is a right side perspective view showing the backrest in folded condition with the armrests and cushions removed for ease of illustration.

The left side of the chair is a mirror image of the right side as shown in FIGS. 1, 5, 6, 7, and 9.

FIGS. 6 through 9 have been drawn to an enlarged scale with respect to FIGS. 1 through 5.

FIG. 1

FIG. 2

FIG. 3

FIG. 4

FIG. 5

FIG. 8

FIG. 9
